UNITED STATES PATENT OFFICE.

PIERRE J. HARDY, OF NEW YORK, N. Y.

DESIGN FOR PICTURE-FRAME CORNERS.

Specification forming part of Design No. 7,506, dated June 30, 1874; application filed May 25, 1874.
[Term of Patent 14 years.]

To all whom it may concern:

Be it known that I, PIERRE J. HARDY, of New York, in the county of New York and in the State of New York, have invented a new and original Design for Corners of Picture-Frames, Panels for Furniture, &c.; and do hereby declare that the following is a full, clear, and exact description thereof, reference being had to the accompanying drawing, making a part of this specification.

My design is intended for the corners of picture-frames, panels of furniture, and is formed by a root or knob, A, from which extend outwardly at right angles two bamboo stalks or branches, parallel to which are a series of four smaller stalks, C, of similar material, one being arranged on each side of said

branches, and having their ends overlapping and curved inwardly toward the center of the root A, from the face of which latter the said stalks spring, all as clearly shown in the accompanying drawing.

Having thus fully described my invention, what I claim as new is—

The design for the corner of a picture-frame, panel, &c., substantially as described and shown.

In testimony that I claim the foregoing I have hereunto set my hand this 20th day of May, 1874.

PIERRE J. HARDY.

Witnesses:

JOHN R. YOUNG,
H. C. HAZARD.
